CLAIM

The ornamental design for a display screen with a transitional icon, as shown and described.

DESCRIPTION

FIG. 1 is a first image in a sequence of a display screen with a transitional icon, showing the new design; and, FIG. 2 is a second image thereof.

The appearance of the transitional icon sequentially transitions between the images shown in FIGS. 1-2.

The process or period in which one image transitions to another image forms no part of the claimed design.

The broken lines shown in the drawings illustrate a display screen or portions thereof, and form no part of the claimed design.
